BRAKE DRUM GAGE

Francis F. Hittle, % Under Car Parts Supply, 8143 Commonwealth Ave., Buena Park, Calif.

Filed May 17, 1962, Ser. No. 70,181

Term of patent 14 years

(Cl. D52—6)

FIGURE 1 is a top plan view of the brake drum gage showing my new design;

FIGURE 2 is a perspective view thereof;

FIGURE 3 is an end view thereof.

I claim:

The ornamental design for a brake drum gage, as shown.
